PIERRE (CALLED) GASTON BAQUEY

GREASE TUBE FOR FACIAL MAKE-UP

Filed Sept. 30, 1925

UNITED STATES PATENT OFFICE.

PIERRE (CALLED) GASTON BAQUEY, OF COLOMBES, FRANCE.

GREASE TUBE FOR FACIAL MAKE-UP.

Application filed September 30, 1925, Serial No. 59,641, and in France October 4, 1924.

It is known that make-up and the like greases in stick or pencil form for the lips and eyes, are contained in sheaths or holders generally furnished with a feed device, the stick or pencil passing out through an aperture of cross-sectional dimensions corresponding with the transverse section of this stick or pencil. In use, the tops of these lipsticks, or the like pencils lose their tapered shape necessary for their proper use, no part of the sheath or holder tending to maintain such shape.

The present invention avoids this inconvenience; it consists of a grease-tube, lipstick or the like characterised by this that the stick or pencil in its ascent from the tube is guided between two or more fixed plates or blades, of which the upper ends, spaced apart, are tapered and shaped or trimmed in such a way as to form a cone or a cylinder tapered in the form of a wedge.

On the annexed drawing, by way of example,

Figure 1 shows in elevation a grease tube 25 for the lips.

Figure 2 is an elevation at right angles to the first, and

Figure 3 is a plan view thereof.

Figure 4 is a section, on a larger scale, on 30 line A—A of Figure 1.

Figure 5 is a section on B—B of Figure 4.

Figures 6 and 7 are two detail views showing the assembly of the parts.

Figure 8 is a section on line C—C of Figure 35 6.

Figure 9 shows in vertical section a modified construction of the grease-tube, specially intended for shading around the eyes, the tube having its cap closed.

Figure 10 is a section thereof on line D—D of Figure 9. Figure 11 is an elevation thereof, part section, with the cap opened.

In the example shown in Figures 1 to 8, the stick or pencil 1 for application to the lips, is held between four guide blades 2 of the shape shown in section in Figures 5 and 8, having their upper ends tapered and bevelled as at 3 in pairs, in such a way that the whole four blades will present the general appearance of a wedge or whistle mouth-piece. The blades 2 are socketed or set in a base member 4 provided with a milled disc 5 and they are secured in this base member by a key or wedge 6 of wood or other material.

The pencil 1 rests upon a star-shaped plate 7 fitting closely to the inner faces of the blades 2 and provided with tongues 7¹ (Figures 6 and 8) engaging in the longitudinal gaps between them. A thin ring 8 with 60 four evenly spaced cuts extending up from its lower edge and provided with a circular groove 9 and with four notches 10 is secured, during the assembly, in a tube 11 having a longitudinal groove 12 in which there can 65 slide a spur or pin 13 fast with the ring 8. The extremity of this pin passes into a straight groove 14 formed in a sleeve 15; this straight groove of short length is continued by a helicoidal incline 14¹ continued 70 spirally along the whole of the sleeve 15; this sleeve 15 rests upon a shoulder 11¹ on the tube 11 and it is also enclosed and held in a socket 16 screw threaded at its lower part (Figures 4 and 7).

After the stick 1 has been inserted in the guide blades 2 and the latter have been seated in their holder or base 4, the blades are passed through the ring 8 until the tongues 7¹ enter the notches 10. By pushing 80 up the base 4, the tongues 7¹ are made to force the ring 8 up into the tube 11, the four parts of its base being thus brought inwards together, which closes the notches 10 and secures the tongues 7¹ of the plate 7. At the 85 moment when the pin 13 of the ring 8 reaches the end of the straight groove 14, the ring enters completely into the tube 11, while the stick 1 and the blades 2 pass beyond the outer socket or casing 16 to a suitable extent. 90 The base 4 is then capped with a sheath or cover 17 of which the upper part is screw threaded to the base of the socket or casing 16. A contracted or inturned portion 18 of the cover 17 prevents the base 4 from becoming loose whilst allowing it to be turned. The tube is thus ready for use, see Figure 4.

The stick is passed between the lips of the user in such a way that the oblique or chamfered surfaces 3 of the blades 2 bearing 100 against them as the lips are smeared, cause the uniform or regular wearing away of the product so that it retains this shape.

In order to move the stick or pencil of salve or grease outwardly from the tube 105 as it is used up, it is sufficient to turn the base 4 by means of the milled disc 5 which effects the rotation of the ring 8; the pin 13 which is fast thereto enters in the helical inclined groove 14¹ which ensures its up- 110

ward movement along the tube 11 and consequently that of the ring 8, of the plate 7 and of the stick 1 which rests upon this latter.

5 In the constructional modification relating to a tube for a pencil for the eyes or eyebrows (Figures 9 to 11), the grease slides between two parallel blades 19, tapered and rounded off at their ends. The feed or advance of the grease is caused by a ring 20 fast with a horizontal bar 21 upon which the grease rests. The two parallel blades 19 are fast with two segmental portions of tubes 19¹. The blades and the tubular segments can be made by suitable folding from the same sheet of thin metal. The tube so formed is located inside another tube 22 of which the cigar-shaped extremity is pierced with a hole 23 and with two longitudinal slots 24 for the passage of the cross member 21. The tube 22 is covered with a sheath 25 furnished with a lid or cap formed by two jaws 26 mounted upon the sheath by means of two plate springs 27 tending to close them together. Two slots 25¹ formed in the sheath 25 permit the passage of guides 20¹ fast with the ring 20. The cap automatically opens as soon as the tube 22 is pushed forward and similarly it closes as soon as the tube is brought back rearwardly.

It will thus be seen that the grease or other substance 1 is fed forward from the

holder or container through the contracted mouth and guided between the inturned edges of the separate shell-plates 2, and that consequently the grease issuing from said mouth does not become smeared indiscriminately in all directions.

The invention is not limited to the details of construction which can be varied without departure from the spirit of the invention. It is further understood that the cap described as applied to the tube containing the pencil for the eyes might also be applied to the grease-stick for the lips, and that the arrangements indicated in the construction of the two grease tubes might be combined together.

What I claim is:—

A grease tube for facial make-up purposes including a grease holder having parallel guide pieces spaced longitudinally to provide slots through which grease will be extruded when subjected to pressure, the edges of the guide pieces along the slots constituting means for sliding engagement with the lips during the application of the grease and for smoothing the grease upon the lips, the free ends of the guide pieces being tapered, and means for shifting the grease longitudinally between the guide pieces toward the tapered ends.

PIERRE (CALLED) GASTON BAQUEY.
